Upgraded Hanging Shower Caddy for Handheld Shower Heads, Adjustable Height Extra Long Bathroom Shower Organizer Hanger Rack with Hooks, Soap Holder, amazon.com, Sep. 3, 2024, Sewulidun, <https://www.amazon.com/dp/B0DFYHRXG5>, (Last accessed : Dec. 19, 2024).

Primary Examiner — Nathan M Johnston

(74) *Attorney, Agent, or Firm* — Jose Cherson Weissbrot

(57) **CLAIM**

The ornamental design for a hanging shower caddy, as shown and described.

DESCRIPTION

FIG. 1 is a perspective view of a hanging shower caddy, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the hanging shower caddy that form no part of the claimed design.

1 Claim, 6 Drawing Sheets
